UNITED STATES PATENT OFFICE.

JOHN F. BRODOWSKI AND GEORGE J. BURMEISTER, OF MILWAUKEE, WISCONSIN.

PANEL LOCK.

Application filed October 31, 1921. Serial No. 511,755.

To all whom it may concern:

Be it known that we, JOHN F. BRODOWSKI and GEORGE J. BURMEISTER, both citizens of the United States, and residents of Milwaukee, in the county of Milwaukee and State of Wisconsin, have invented certain new and useful Improvements in Panel Locks; and we do hereby declare that the following is a full, clear, and exact description thereof.

The invention is a device to lock and clamp a panel upon a frame.

It is an object of the invention to facilitate the ready installation of a screen for storm panels by means of a lock operating to clamp the panel in position.

It is a further object to eliminate looseness and rattling of panels.

Further objects will be apparent as the description proceeds.

Figure 1 shows a horizontal sectional view taken immediately above the lock.

Figure 2 shows an elevation on the line 2-2 of Figure 1.

Figure 3 is a cross section on the lines 3-3 of Figure 2.

Figures 4, 5 and 6 are details of the lock mechanism.

The invention is described more in detail. A door frame 1 engages with a panel frame 2, carrying a glass 3. The door frame 1 has a chamber 4 for receiving the lock plate 5, having lugs 6 thereon for retention in the door frame and carrying a pivot 7 thereon encircled by spiral spring 8. Upwardly directed from said plate 5 is a flange 6' having thereon, a finger 6''. Rotatably mounted on said pivot 7 is a locking member 9, shown in Figure 5 and in dotted lines in Figure 6.

The portions of the lock nearest the observer when viewed in Figure 2, are referred to as the upper portions. Locking member 9 has on its lower surface two radial grooves 10. On its upper surface are shoulder portions 11. Gradually deepening grooves 11' terminate at these shoulders. Concentrically rotatable with said locking member 9 is a disk member 12 having two downwardly directed semi-circular flanges 13 terminating in shoulders 13', and a central upraised boss 14, having therein, a slot 15 adapted to receive the end of a screw driver. Door frame 1 is provided with an aperture 16 to receive boss 14. When spring 8 is in an extended position, as shown in Figure 1, pressure

upon boss 14 operates to move disk 12 and locking member 9 downwardly.

It is thus apparent that when panel frame 2 is removed, the locking pieces may be placed in the position shown by insertion through the side of chamber 4, lugs 6 being forced into the wood.

When the panel frame 2 is placed in position to be engaged by the locking member, rotation of disk member 12 in a clockwise direction causes shoulders 13' to engage with shoulders 11 of the locking member 9. This causes engagement of groove 10 of the locking member with finger 6''. The panel is then locked. A counter clockwise turn of the screw driver in slot 15 causes flanges 13 to ride upwardly in grooves 11', thus causing depression of clamping member 9 and exercising a clamping action upon surface 17 of the panel frame where the locking member contacts. This position of the members, is shown in Figure 1. When it is desired to disengage the panel, a rotation of the screw driver in a clockwise direction causes a reengagement of shoulders 13' with shoulders 11, and disengagement of groove 10 from finger 6''. The locking member 9 is then moved out of locking position. This releases panel frame 2.

It will be noted that locking member 9, when in the position shown in Figure 1, acts as a lever with one of its ends resting on flange 6', flanges 13 pressing upon the central portion.

We claim:

1. The combination with a locking member of a finger for engaging said locking member when in locking position, and means operating in one direction to move said locking member into locking position and in the other direction to clamp said locking member in position.

2. In a panel lock, the combination of a rotatable member, two arms thereon, each having an indentation on one face thereof, two shoulders on the other face thereof, a second rotatable member having flanges thereon cooperating with said shoulders to turn said first mentioned rotatable member in one direction, and operating when turned in the other direction to clamp said first named rotatable member.

3. The combination of a plate, a pivot thereon, a flange extending upwardly therefrom, a finger on said flange, a locking member having grooves therein adapted to

- engage said finger, and means for moving said locking member into locking position and then exercising a clamping action thereon.
5. In a panel lock, the combination of a locking member having two indentations adapted to engage a locking finger, shoulders on said locking member, and grooves increasing in depth to said shoulders, a disk 10 having semicircular flanges thereon of increasing depth terminating in shoulders, and a boss on said disk having a slot therein adapted to receive a screw-driyer.
5. In a panel lock, the combination of a

plate having a projection thereon for holding said plate in position, a flange on said plate, a finger on said flange, a pivot on said plate, a spiral spring encircling said pivot, a locking member rotatable on said pivot, and means for rotating said locking member in one direction and clamping said locking member when in locking position.

In testimony that we claim the foregoing we have hereunto set our hands at Milwaukee, in the county of Milwaukee and State 25 of Wisconsin.

JOHN F. BRODOWSKI.
GEO. J. BURMEISTER.
